COMBINATION DOOR PROTECTOR AND
LOCK

Gordon Grant McDonald, Nova Scotia, Nova Scotia, Canada, assignor to Edna P. Cox, Halifax, Nova Scotia, Canada

Application August 10, 1936, Serial No. 95,263

3 Claims. (Cl. 292—269)

This invention relates to door fasteners and has for the primary object the provision of a simple and inexpensive device of this character which will be simple and convenient to mount and which may be readily operated to secure a door in fully closed position against being opened from the outside of said door or may be operated to secure the door in a partly open position against being fully opened or sufficient to permit entrance from the outside of said door, whereby ventilation may be had through the doorway from the outside without danger of an intruder entering.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a fragmentary front elevation showing a door fastener constructed in accordance with my invention and applied to a door and a door frame.

Figure 2 is a fragmentary longitudinal sectional view showing the door secured in a partly open position by the fastener.

Figure 3 is a view similar to Figure 2, showing the door secured in a fully closed position by the fastener.

Figure 4 is a fragmentary front elevation showing the fastener positioned to permit the securing thereof to the door and door frame by screws and like fasteners.

Figure 5 is a sectional view taken on the line 5—5 of Figure 2.

Figure 6 is a perspective view of an attaching plate employed upon the door.

Figure 7 is a perspective view illustrating an attaching plate employed on the door frame.

Figure 8 is a fragmentary longitudinal sectional view showing a modified form of my invention.

Referring in detail to the drawings, the numeral 1 indicates a fragmentary portion of a door and 2 indicates a fragmentary portion of a door frame. Secured to the door 1 and the door frame are attaching plates 3 and 4. These plates are provided with openings 5 to receive screws or like fasteners 6' for securing the attaching plates to the door and to the door frame. Formed on opposite edges and overlying the attaching plates are retaining members or jaws 6. The jaws or members 6 of each attaching plate extend in opposite directions to each other and provide therebetween a space on the attaching plate to receive

a connecting member. The connecting members for the attaching plates 3 and 4 are indicated by the characters 7 and 8. The attaching member 7 has a slot 8' to receive a rivet or like fastener 9 secured to the attaching plate 3 whereby the attaching member 7 may be positioned to parallel the attaching plate or be positioned to extend at right angles thereto and when in the latter-named position exposes the openings of the attaching plate so that the screws or fasteners 6' can be threaded into the door. The screws or fasteners are covered by the attaching member 7 when positioned to parallel the attaching plate and when in the latter-named position is overlapped by the jaws or members 6. The slot 8' permits the attaching member 7 to pivot relative to the attaching plate 3 and also to have a limited sliding movement relative thereto. Formed on one end of the attaching plate 3 are spaced hook-shaped elements 10, the free ends of which are positioned to overlie said attaching plate 3. Formed on the attaching member 7 adjacent one end is an arcuately curved finger 11 of a length so that its free end protrudes beyond one end of said attaching member 7 and is provided with pairs of notches 12 and 13. The notches of each pair extend inwardly from opposite sides of the finger 11, the notches 13 being located adjacent to the point of formation of the finger to the attaching member 7 while the notches 12 are located adjacent the free end of the finger. The finger may be employed by a person to obtain a grip on the attaching member 7 for the purpose of sliding or pivoting the latter and also the finger operates in conjunction with a securing plate 14. The attaching member 7 when moved endwise in one direction relative to the attaching plate 3, the finger is received between the hook-shaped members 10 to prevent the attaching member from pivoting and moving out of parallelism with the attaching plate 3.

An attaching member 15 is pivoted to the attaching plate 4 and may be positioned to extend parallel with the latter or positioned to extend at right angles thereto. The attaching plate 4 has fingers or jaws similar to the fingers or jaws 6 of the attaching plate 3 and which overlie the attaching member 8 when paralleling the attaching plate 4. Hinged to one end of the attaching member 8 is the securing plate 14 and the latter has formed therein a slot 16. Also formed in the securing plate 14 are openings 17 and 18 they being in communication with the ends of the slot 16. The opening 17 is located adjacent the hinge which connects the secu-

ing plate to the attaching member 8 and is of a size which will permit the finger 11 to pass freely therethrough. The width of the slot 16 is such that the finger cannot move therethrough unless 5 the finger is so positioned as to bring the notches 13 in position to receive the walls of the slot 16. The opening 18 is slightly larger than the slot 16 in width and opposite walls thereof are adapted to extend into the notches 12 of the finger 10 during a certain use of this invention and which will be hereinafter more fully described.

In operation, to secure the door in a fully closed position, the attaching member 1 is moved endwise to bring the finger 11 between the hook-shaped members 10 and the attaching member 8 is positioned to parallel the attaching plate 4 and the securing plate is swung to overlie the attaching plate 7 with the finger 11 projecting through the opening 17. The notches 13 of the 20 finger are then in alignment with the opposite walls of the slot 16 so that the attaching member 1 may be slid in an opposite direction with the finger occupying a position in the slot 16 at some point between the openings 17 and 18. 25 The securing plate then is firmly secured to the attaching member 7 so that the door cannot be opened.

When desiring to employ this invention for securing the door in a partly open position, as 30 shown in Figure 2, the securing plate is swung at an angle to the attaching plate 8 with the finger 11 occupying a position in the opening 18, the notches 12 then receiving the opposite walls of the opening 18. The door is then secured 35 slightly ajar from the door frame sufficient to permit ventilation and not far enough from the door frame as to permit an intruder to enter.

Referring to my modified form of invention, as 40 shown in Figure 8, a slight rearrangement of parts is shown from that disclosed by the other views of the drawings so that instead of applying the securing plate on the door frame it may be secured to the door, that is, the attaching plate 4 is secured to the door with the attaching member pivoted thereto. With this arrangement a 45 slightly different construction of securing plate 20 is employed and is secured to the door frame and a finger 21 forms an integral part thereof and extends at right angles thereto. The finger 50 21 operates in the slot of the securing plate 14 as heretofore described and when the door is secured in a fully closed position the fasteners employed for securing the attaching plate 20 to the door frame are overlapped thereby.

55 Having described the invention, I claim:

1. A door fastener comprising an attaching plate secured to a door, a second attaching plate secured to a door frame, an attaching member pivotally and slidably connected to the first-named attaching plate and capable of extending parallel therewith or at right angles to the length thereof, a second attaching member pivoted to the second-named attaching plate and capable of extending parallel therewith or at right angles 60 to the length thereof, jaws formed on the at-

taching members and the jaws of each attaching member extending in opposite directions to each other and adapted to overlie the attaching members when in parallelism with the attaching plates, and separable means connected with the attaching plates for securing the door in a closed position or in a partly open position. 5

2. A door fastener comprising an attaching plate secured to a door, a second attaching plate secured to a door frame, an attaching member pivotally and slidably connected to the first-named attaching plate and capable of extending parallel therewith or at right angles to the length thereof, a second attaching member pivoted to the second-named attaching plate and capable of extending parallel therewith or at right angles to the length thereof, jaws formed on the attaching members and the jaws of each attaching member extending in opposite directions to each other and adapted to overlie the attaching members when in parallelism with the attaching plates, spaced hook-shaped members formed on one end of the first-named attaching plate, a curved finger formed on the first-named attaching member and when positioned to lie between the hook-shaped members prevents pivotal movement of the first-named attaching member, and means connected to the second-named attaching member to coact with the finger in securing the door in a closed position or in a partly open position. 20 25 30

3. A door fastener comprising an attaching plate secured to a door, a second attaching plate secured to a door frame, an attaching member pivotally and slidably connected to the first-named attaching plate and capable of extending parallel therewith or at right angles to the length thereof, a second attaching member pivoted to the second-named attaching plate and capable of extending parallel therewith or at right angles to the length thereof, jaws formed on the attaching members and the jaws of each attaching member extending in opposite directions to each other and adapted to overlie the attaching members when in parallelism with the attaching plates, spaced hook-shaped members formed on one end of the first-named attaching plate, a curved finger formed on the first-named attaching member and when positioned to lie between the hook-shaped members prevents pivotal movement of the first-named attaching member, a securing plate hinged to the second-named attaching member and having a slot and opening located at each end of the slot and in communication therewith and one of said openings being larger than the other to permit free passing of the finger therethrough, said finger having pairs of notches and one pair of notches adapted to receive opposite walls of the slot to permit sliding movement of the first-named attaching member and the other pair of notches adapted to receive opposite walls of the largest opening for securing the attaching plate to the finger and at an angle to the second-named attaching member for securing the door in a partly open position. 40 45 50 55 60 65
